UNITED STATES PATENT OFFICE.

JAMES KEMNAL, OF LONDON, ENGLAND, ASSIGNOR TO THE BABCOCK & WILCOX COMPANY, OF BAYONNE, NEW JERSEY, A CORPORATION OF NEW JERSEY.

BOILER FURNACE.

Application filed July 26, 1924. Serial No. 728,430.

To all whom it may concern:

Be it known that I, JAMES KEMNAL, a subject of the King of the United Kingdom of Great Britain and Ireland, and residing at 5 London, England, have invented certain new and useful Improvements in Boiler Furnaces, of which the following is a specification.

My invention relates to furnaces for steam generators and will be best understood from the following description taken with the annexed drawings in which Figure 1 is an elevational view partly in vertical section of an illustrative embodiment of my invention and Figure 2 is a section taken on the line 2—2 of Fig. 1.

In said drawing 10 denotes an arch formed of refractory masonry disposed between a mechanical stoker 11 and roof 12 of a combustion chamber. It will be noted that the front end of arch 10 is spaced from the front wall 13 of the combustion chamber and, preferably, the rear end of arch 10 is also spaced from the rear wall 14 of the furnace 25 chamber 15. By such arrangement a portion of the gases evolved from the fuel on grate 11 will pass around the forward end of arch 10 through the space between the upper side of said arch and the roof 12 of 30 the combustion chamber and into the furnace chamber 15.

Due to the fact that arch 10 would thus be subjected to heat on both sides, it would ordinarily be liable to collapse. To obviate 35 this difficulty I preferably interpose between arch 10 and roof 12 a plurality of open-ended, hollow, retort-like structures 16 in abutting relation, and themselves constituting the voussoirs of an arch, for which are provided abutments 17, 17. Advantageously, I line the ends of structures 16 with a layer of refractory bricks 17^a. Preferably, structures 16 are provided with keyways 18 for the reception of keys (not shown) in 40 order to form a stronger arch.

Due to the highly heated arch 10 my improved furnace will be particularly adapted for burning fuels having a high percent of moisture and for low grade fuels in general. The mixture of gases evolved in the forward part of the grate and the air there introduced will be carried through the retort-like structures 16 where, due to such increased length of travel, and to the highly heated condition of the surrounding mason-

ry, ample opportunity will be given for the combustion of such gases. Otherwise, the gases evolved on this portion of the grate might not be given sufficient opportunity for mixing with the air and for combustion therewith, and, in addition, might interfere with the combustion of the gases evolved at the rear portion of the grate. On the other hand, the gases evolved at the rear end of the grate, due to the fact that their temperature is considerably higher, undergo combustion more readily and the necessity for giving them a long path of travel does not arise.

Moreover, due to the supporting and protecting action of structures 16, arch 10 is effectively protected against the destructive effect of the heated gases on both sides thereof.

I claim:

1. In a boiler furnace, a combustion chamber, an arch disposed intermediate the furnace grate and the roof of said chamber and having the front end thereof spaced from the front wall of the combustion chamber and a plurality of structures having longitudinal passages in the space between said arch and the roof of said chamber protecting the upper side of the arch from the flames and affording a passage for the products of combustion therethrough to the furnace chamber.

2. In a boiler furnace, a combustion chamber, an arch disposed intermediate the furnace grate and the roof of said chamber and having the front and rear ends thereof spaced from the front wall of said chamber and the rear wall of the furnace chamber respectively and a plurality of structures having longitudinal passages therethrough in the space between said arch and the roof of said chamber protecting the upper side of the arch from the flames and affording a passage for the products of combustion therethrough to the furnace chamber.

3. In a boiler furnace, a combustion chamber, an arch disposed intermediate the furnace grate and the roof of said chamber and having the front end thereof spaced from the front wall of said chamber and a plurality of structures having longitudinal passages therethrough in the space between said arch and the roof of said chamber protecting the upper side of the arch from the flames and affording a passage for the prod-

ucts of combustion therethrough to the furnace chamber and means for supporting said structures independently of said arch.

4. In a boiler furnace, a combustion chamber, an arch disposed intermediate the furnace grate and the roof of said chamber and having the front end thereof spaced from the front wall of said chamber and a plurality of structures having longitudinal passages therethrough in the space between said arch and the roof of said chamber protecting the upper side of the arch from the flames and affording a passage for the products of combustion therethrough to the furnace chamber, said structures themselves forming the voussoirs of an arch and abutments for such arch.

5. In a boiler furnace, a combustion chamber, an arch disposed intermediate the furnace grate and the roof of said chamber and having the front end thereof spaced from the front wall of said chamber and a plurality of structures having longitudinal passages therethrough in the space between said arch and the roof of said chamber protecting the upper side of the arch from the flames and affording a passage for the products of combustion therethrough to the furnace chamber, said structures being keyed together and themselves forming the voussoirs of an arch and abutments for such arch. 20 25 30

JAMES KEMNAL.
